United States Patent Office.

DAVID WEISER, OF PHILADELPHIA, PENNSYLVANIA.

Letters Patent No. 78,164, dated May 19, 1868.

IMPROVEMENT IN HAMMER-HANDLES.

The Schedule referred to in these Letters Patent and making part of the same.

TO ALL WHOM IT MAY CONCERN:

Be it known that I, DAVID WEISER, of Philadelphia, Pennsylvania, have invented an Improved Hammer; and I do hereby declare the following to be a full, clear, and exact description of the same, reference being had to the accompanying drawing, and to the letters of reference marked thereon.

My invention consists of a mode, described hereafter, of securing the handles to the heads of hammers, or of other tools or implements.

In order to enable others skilled in the art to make and use my invention, I will now proceed to describe its construction and operation.

On reference to the accompanying drawing, which forms a part of this specification—

Figure 1 is a perspective view of the head of my improved hammer.

Figure 2, a perspective view of a portion of the handle, and the device for securing the same to the shaft.

Figure 3, a section on the line 1-2, fig. 1.

Figure 4, a section of the hammer-head and part of the handle inverted; and

Figure 5 an inverted plan view of the hammer-head.

Similar letters refer to similar parts throughout the several views.

A is the hammer-head, of which a is the pole and b the pene. In the under side of the head is a recess, e, of the dove-tailed form, best observed on reference to fig. 4. To the handle, D, of the hammer, is tightly fitted the collar B, from which project the two jaws or cheek-pieces, d and d', the ends of the latter being so bevelled as to fit into the dove-tailed recess e, in the under side of the head.

In order to introduce the bevelled ends of the cheek-pieces into the recess, the latter are compressed towards each other, (the handle, B, not being yet in its place,) then deposited in the recess, and afterwards permitted to spring outwards, apart from each other. The handle, D, is now driven into its place, so as to extend to the end of the recess in the head, and act as a wedge to force the said cheek-pieces apart from each other, and prevent the withdrawal of their ends from the recess.

In the pene b is cut an opening, part of which, f, is circular, and large enough to admit the head of an ordinary nail. The other portion, h, of the opening, is narrow, wide enough only to admit the stem of a nail, and is bevelled, as shown in fig. 3.

The hammer, when used for extracting nails, is applied in the manner illustrated in fig. 4, the enlarged portion, f, of the opening, being placed over the head of the nail, and the head of the hammer pushed forwards, so that the head may become wedged in the bevelled portion, h, when force may be applied to the handle, in the usual manner, to extract the nail.

Although I have illustrated and described the device as applied to a hammer, it will be apparent that it may be applied to other tools and implements.

I claim as my invention, and desire to secure by Letters Patent—

The handle D, collar B, its cheek-pieces d d', with bevelled ends, adapted to the dove-tailed recess e, in the head of a hammer or other tool or implement, the whole being constructed and arranged substantially as and for the purpose herein set forth.

In testimony whereof, I have signed my name to this specification in the presence of two subscribing witnesses.

DAVID WEISER.
